DRIVING MECHANISM FOR COUNTERS

Walter Ochsenbein, Berne, Switzerland

Application April 1, 1931, Serial No. 526,966, and
in Germany April 12, 1930

6 Claims. (Cl. 235—138)

This invention relates to driving mechanism for counting devices comprising driving wheels having adjustable teeth, such as is preferably used for example in stamping machines, in which as is known only a totalling of the numbers or stamp values takes place.

Various proposals have heretofore been made to secure the number discs of calculating machines against rotation or advance when they are not being driven or are not in moving connection with the driving wheels. As a rule two-armed locking levers are used for this purpose, which levers control with one end a ratchet or other toothed wheel, and are controlled at the other end by cams or stops of the associated driving wheel. In devices in which the driving wheel has to be axially displaced for driving the counter the meshing of the said wheel with the teeth of the counter is accomplished with difficulty when the teeth do not fit one another exactly. In the usual type of this device, the locking lever is held only by a spring and the advantages of a positive lock are lost.

The present invention has for one of its objects to obviate these defects and to ensure in counting mechanism of the kind referred to, particularly for franking stamping machines, a permanent positive lock, namely one wherein no springs are employed.

To this end the locking lever engages with two cams over the laterally projecting driving teeth or over a lateral rim of the driving wheel and is positively moved by the rotating driving wheel out of its one into its other end position and is held therein.

For the tens transfer, the locking lever bears against a member which is in moving connection with a change-over member moved with the tens transfer member so that during the transference of the tens the locking lever is disengaged and is afterwards engaged.

As there are no springs in the entire apparatus the device for driving the counter operates reliably.

Other features of the invention will be described hereinafter and pointed out in the claims.

One embodiment of the invention and a modification thereof are diagrammatically illustrated, by way of example, in the accompanying drawings, wherein:—

Figure 1 is a sectional elevation taken on the line I—I in Figure 2 showing one form of mechanism according to the invention with the number discs locked, and

Figure 2 is a horizontal section taken on the line II—II in Figure 1;

Figure 2a shows a transfer tooth,

Figure 2b shows a driving tooth,

Figure 3 shows a tens transfer lever in its operative position, and

Figures 4 and 5 show the number disc locking device in two different positions;

Figure 6 is a plan of a counter driving mechanism with its associated locking lever and tens transfer lever, and

Figure 7 shows one single tens transfer lever as viewed from above;

Figure 8 is a plan view of a single locking lever of the tens transfer lever; and

Figures 9 and 10 are elevations showing a modification of the tens transfer mechanism in two different positions.

Referring first to Figures 1 to 8 of the drawings, driving wheels 2 are arranged on a horizontal hollow cylinder one beside another as usually in calculating machines of this kind; the teeth 3 of these wheels are movable in radial grooves and engage in known manner with a pin 3b in a lateral groove 4a of a ring 4, so that by turning the latter by means of a handle member 4b or other suitable device they can be pushed outwards and thereby shifted out of the normal or rest position, shown in Figures 1 and 2, into the working position, and reversely. Each tooth 3b has at its outer end a laterally projecting rung 3a which, when the tooth is retracted, lies in a recess in the periphery of the driving wheel. When the cylinder 1 and the driving wheels rotate in the direction of the arrow shown in Figure 1, the teeth shifted radially outward, i. e. into the working position, engage with an intermediate wheel 6 and act through it on a pinion 7 firmly connected with a number disc 8 of the counter.

The rungs of the teeth 3 are situated on the side of the driving wheels in Figure 1 facing the observer. The gear wheel 6 that drives a number disc is controlled by a locking lever 26 freely rotatable on a horizontal fixed axle 25. This lever 26 has two laterally projecting cams 30 and 31 which engage from the side of the driving teeth or lateral row of teeth 3a of the driving wheel and its rim 5 as the wheel rotates.

A plurality of levers 13 each having two lateral dogs or claws 11 and 12 are arranged freely rotatable on the axle 25, one beside the second, third and fourth idler wheels 6 and opposite the associated locking lever 26. The two claws 11 and 12 are bevelled upwards so that they together

form a conical inlet or mouthpiece for a feed rung 14 of a feed tooth 15 that is free to move radially (from below in Figure 2) in the second, third and fourth driving wheels. The tooth 15 carries in line with the rung 14, i. e. on the side of the rungs of the teeth 3, a rung 16 which extends within range of the cams 30 and 31 of the associated locking lever 26.

The tooth 15 is followed on the side of the rung 14 by a resetting pin 17 (Fig. 1) by which, after the tens have been fed, the tens feed lever 13 is returned out of its operative position (Fig. 3) into its rest position.

The tens shifting lever 13 (Fig. 7) has a laterally displaced extension 18 that projects downwards beyond the axle 25 and has a nose 20 extending upwards within reach of a tens shifting cam 19. This cam 19 is firmly connected with the front lower number idler wheel 6 in Figure 3 and at each revolution of the latter moves the lever 13 out of its rest position (Figure 1) into its operative position (Figure 3).

In order that the lever 13 shall remain in the position into which it is adjusted the extension 18 is provided with two notches 21 and 22, with which a pawl 23 engages. This pawl is held in engagement under gravity with one or other of these notches by an arm 24 mounted on the hub of the pawl at one side of the latter. All the pawls 23, and arms 24 are freely rotatable on an axle 25 common to them all. The arm 24 lies in the plane of the rung 14 of the driving wheel belonging to the next order and is guided along the path of this rung.

The feed teeth 15 and pins 17 of the successive driving wheels are staggered relatively to one another on the periphery, and consequently a tens transfer imparted to a counter wheel does not synchronize with a movement by the associated driving wheel imparted to the counter wheel.

The length and position of each arm 24 is such that it is engaged by the pin 17 of the driving wheel of the next higher order to hold the arm from swinging upward during the time of such engagement. The pins 17 and 14 of wheels of successive orders are so spaced circumferentially of the wheels that the pin 17 of one order remains in engagement with the arm 24 which it controls until the pin or rung 14 of the next order has completely passed through the space between the claws 11 and 12 of the corresponding lever 13 and the advancement of the number wheel one digit has been completed. Pawl 23 therefore cannot disengage from notch 22 until this has been accomplished and the pin or rung 17 moved to free arm 24. Consequently the lever 13 cannot, prior to this, be forced out of feeding position in case moving of the tens feed rung in one direction or the other is hindered by thickening or lubricating oil, or by other cause.

When the driving wheels rotate, the pawls 26 are controlled by the rungs in the manner described above, i. e. the pawls are brought into and out of engagement with the driving wheel 6 in that manner. For feeding the tens, hundreds and thousands discs, when a change occurs from 9 to 0 the tens feed lever 13 is reversed from its rest position (Figure 1) into its operative position (Figure 3) by the tens feed cam 19. When the feed tooth 14, 15 of the appertaining driving wheel enters between the claws 11 and 12 of the tens feed lever 13, the feed tooth is so set by the one claw or the other, according to the momentary position of the tooth, that it engages with the driving wheel 6 of the number disc. The rung 16

simultaneously engages with the locking lever 26 and forces the same out (see Figure 5). In order to permit the tooth 14 to move inwardly of the "driving" wheel the lateral rim 5 of the driving wheel has at its feed tooth a recess 16' to receive the rung 14. As soon as the tens feed is finished the tens feed pawl 13 is turned back by the pin 17 into its rest position, and the locking lever 26 is brought into engagement again with the driving wheel 6 by the side rim 5 of the driving wheel.

By means of this counter driving device quiet, i. e. noiseless operation is obtained even when the machine, e. g. a franking stamping machine in which the counter is incorporated, runs at an abnormally high speed and several values are fed quickly one after another.

According to the modification shown in Figures 9 and 10, the safety lever 24 of the construction illustrated in Figures 1 to 8 is formed as a weighted lever for the pawl 23, and on the tens feed lever 13 a locking rim 32 is arranged beside the claw 12 so as to provide a groove 33. A locking pin 34 projecting laterally from the corresponding driving wheel 2 coacts with the rim or edge 32 in such a manner that when the pin 34 passes on the inner or outer side of the rim 32 the tens feed lever cannot be reversed from its one to its other end position before the feed tooth 14, 16 has passed between the claws of the tens feed lever 13 and of the locking lever, not shown, and feed of the tens has occurred. The feed teeth of the various driving wheels are likewise staggered relatively to one another.

As will be understood from the above the locking of the idler wheel for the number discs is controlled positively both during the drive by the driving wheels and also when the tens are being transferred. No springs are present in the entire mechanism, and consequently breakdowns due to broken springs cannot occur.

I claim:—

1. In a machine of the kind described, wherein driving wheels have adjustable teeth, a counter driving mechanism comprising number-disc idler-wheels cooperating with the driving wheels, and locking levers normally locking the idler wheels which locking levers have each two cams extending transversely of laterally projecting rungs on the driving teeth, and are arranged to be adjusted positively by the rotating driving wheels out of the one and into the other end position and to be held therein.

2. In a machine of the kind described, wherein driving wheels have adjustable teeth, a counter driving mechanism comprising number-disc idler-wheels cooperating with the driving wheels, and locking levers normally locking the idler wheels, which locking levers have each two cams extending transversely of a lateral rim on the corresponding driving wheel, and are arranged to be adjusted positively by the rotating driving wheels out of the one and into the other end position and to be held therein.

3. Counter-driving mechanism comprising in combination an idler wheel of one order, a cam 140 rotatable therewith, a second idler wheel of the next higher order, a locking lever for controlling said second wheel, a feed tooth that is movable on a driving wheel and has two rungs, whereof one controls said lever, a control lever having 145 two arms whereof one carries two lateral claws for coacting with the second rung and controlling said tooth, the second arm of which control lever is so adjusted by said cam that said tooth is brought by the control lever into engage- 150

ment with the second idler wheel, the locking lever is disengaged from the latter, and the second idler wheel is fed one tooth.

4. Counter driving mechanism according to claim 3, wherein the control lever for the tens has an extension with two notches, a pawl serves for engaging therewith, which pawl is firmly connected with a loaded arm displaced laterally relatively thereto, which loaded arm is situated in the plane of the rung of the next driving wheel in front thereof and is of such length that it allows a reversal of the control lever having claws for feeding the tens only when its path of oscillation is liberated by a resetting pin that follows the row of rungs.

5. Counter driving mechanism according to claim 3, wherein the control lever having claws carries a locking rim providing a groove between it and a claw, with which rim a locking pin provided on the corresponding driving wheel cooperates in such a manner that the reversal of the control lever for feeding the tens out of its one into its other end position is not possible as long as the feed tooth is situated between the claws of the locking lever and the control lever and the tens transference is not completed.

6. In a device of the kind described, a driving wheel, a radially movable member carried by said driving wheel and provided on its outer end with aligned rungs projecting from opposite sides thereof, an idler wheel for one order of digits carrying a transfer cam, a second idler wheel for the next order of digits, said member being arranged to engage the second idler wheel and rotate the same one tooth space for each complete revolution of the first idler wheel, a locking lever having a lug engaging between the teeth of the second idler wheel and provided with a pair of spaced and flaring jaws between which the rung on one side of the member passes, said jaws being arranged to cam the lever upon passage of the rung and thereby free the second idler wheel, a second lever having similar jaws between which the remaining rung passes, a lug on the second lever normally in the path of the transfer cam, and means to positively latch the second lever against movement by the transfer cam until the last mentioned rung has passed through the space between said jaws.
